Orlando Mack of Gilsum, New Hampshire.

Patented April 2nd 1835.

Letters Patent

The Schedule referred to in these Letters Patent and making part of the same containing a description in the words of the said Orlando Mack himself of his improvement in the construction of a ~~Door~~ ^{Door} and that the following is a full and exact description of the construction thereof as improved by me.

To all to whom these present shall come. Be it known that I Orlando Mack of Gilsum in the County of Cheshire and State of New Hampshire, have invented a new and useful improvement in the construction of a ~~Door~~ ^{Door} and that the following is a full and exact description of the construction thereof as improved by me.

The improved ~~Door~~ ^{Door} is called the secretary ~~Door~~ ^{Door}. It is composed of boards in several parts, but for ease of description it may be taken to be eighteen inches high, and twelve inches square top and bottom, ^{inside} having two doors, one on the front ~~and one~~ ^{and one} on the back, both swinging one way. The doors should extend from the top board of the ~~Door~~ ^{Door} down eight inches and the whole width of the ~~Door~~ ^{Door}. Put a partition across the ~~Door~~ ^{Door} parallel with the bottom of the doors, ten inches wide, dividing into two parts, ^{up} ~~up~~ ^{and down} & leaving a space of three fourths of an inch between the edges of the partition board & the sides of the ~~Door~~ ^{Door}. In each edge of this partition board there should be a groove, one twelfth of an inch in width and one fourth deep, running the whole length of the board. Then in the edges of one of the flank pieces on which the doors are hung, cut horizontally and parallel with the above mentioned grooves, two holes one on each edge of the board, one inch in width and one twelfth of an inch in diameter. Make two knives or slides fourteen inches long, the distance of the handles one inch in width and one half inch thick. Then by inserting these slides into the last mentioned holes and sliding them inwards in the grooves in the edges of the partition board, the doorway between the sides of the ~~Door~~ ^{Door} and the edges of the partition board is stopped. The upper part of the ~~Door~~ ^{Door} should then be divided into two equal parts by putting a board

perpendicularly and parallel with the doors. so that each door shall open into a separate part. These two separate parts or chambers as they may be called. may be filled with boxes or draws having one on each side long enough to fill up the chamber. or several smaller ones or none at all. These draws should be made with front sides and tops and bottoms. there must be a space of about three fourths of an inch between the bottom board and the front of the draw so that by taking out the sides the hole in the bottom of the draw will come directly over the hole which the sides stop leaving a free passage for the Bees out of the lower part of the hive into these draws. The Bees will then fill these draws with comb & Honey. Then by slipping these sides and stopping the bees from passing up you may take out the draws and add place in new ones. and in this way by changing the draws when they are filled you may take fifty pounds of honey without disturbing the Bees in one season. if the season is favourable. When the draws are full with old sides should be taken out and the doors shut. and when the draws are taken out the sides should be put in and the doors opened. Then the Bees will come out and go into the lower part of the hive. If the Bees should not lay on long enough in the lower part of the hive to keep them through the winter season. having their bees taken out can be replaced in the hive again. but the bees have filled another part of the hive as what may be called a nest. If so it is a piece of thin iron say the thickness part of an iron nail bent up and one inch wide. this should be flat and not in a curve for nearly as large as the bottom of the hive. the rest of the part of it may be called should not meet each other into two corners of a half leaving a space in the centre of one side of the half bend about one inch on each end directly out from the centre. so that the space on the side of the half may be three inches in length. Then if this half must then be inserted into the bottom of the hive so as to hold it in firmly. through the space in the front of the half and the ends even with the rest of the parts of the hive. Then the rest of the hive may be closed up with the rest of the parts of the hive.

May

go under through the span in the hoop. Then there is no chance for the
Bee moth or miller to lay their eggs under the edge of the Hive.
The Bee moth is the greatest foe of the honey Bee. One which neither the
instinctive powers of self preservation with which the Bee is endued
is able to resist nor her to fore in the ingenuity and skill of man
has not been able effectually to provide against. There may be a
slide door made of iron with small holes sufficient to let in
the air into the hive so as to shut the bees into the hive or others
out in case of robbing. That I claim as my invention and for
which I ask an exclusive privilege is the mode of constructing a Bee
Hive with apartments in such a manner as by the use of a slide to
shut the Bees from different apartments and thereby take out
Honey at any time without罗lling the Bees. Also the construction
of an iron hoop attached to the bottom of the hive so as to prevent
the miller or moth from getting into the hive.
